[57] CLAIM

The ornamental design for a combined vehicle hood
and warning units, as shown and described.

DESCRIPTION

FIG. 1 is a side elevation view of a combined vehicle
hood and warning units showing our new design;

FIG. 2 is a top plan view thereof;

FIG. 3 is an enlarged front elevation view thereof;

FIG. 4 is a greatly enlarged fragmentary perspective
view of the left front portion thereof showing one of the
warning units in greater detail;

FIG. 5 is a slightly enlarged top plan view of FIG. 4;

FIG. 6 is a right side elevation view of FIG. 5 showing
the warning unit separately for convenience of illustration;

FIG. 7 is a left side elevation view of FIG. 5 showing
the warning unit separately for convenience of illustration;
and,

FIG. 8 is a front elevation view of FIG. 5.

The broken line showing of a vehicle in FIGS. 1, 2 and
3 of the drawing is for illustrative purposes only and
forms no part of the claimed design.
